Patented Dec. 18, 1973

229,590

CHILD'S SWING SEAT

Paul W. Ahrens, Grinnell, Iowa, assignor to Miracle
Equipment Company, Grinnell, Iowa

Filed Aug. 31, 1970, Ser. No. 24,769

Term of patent 14 years

Int. Cl. D6—02

U.S. Cl. D6—11

FIG. 1

FIG. 3

FIG. 1 is a front perspective view of a child's swing seat showing my new design;

FIG. 2 is a top plan view; and

FIG. 3 is a rear elevational view.

I claim:

The ornamental design for a child's swing seat, substantially as shown.
